UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

SAVINGS-BANK.

1,157,303.

Specification of Letters Patent.

Patented Oct. 19, 1915.

Original application filed March 11, 1912, Serial No. 683,178. Divided and this application filed April 24, 1913. Serial No. 763,327.

To all whom it may concern:

Be it known that I, CHARLES FISHER, a citizen of the United States, residing at Chicago, in the county of Cook and State 5 of Illinois, have invented new and useful Improvements in Savings-Banks, of which the following is a specification.

My invention relates particularly to savings-banks provided with several coin-compartments adapted to keep the coins of different denominations separate from each other to facilitate counting of the coins when the savings bank is taken to the banking institution for the purpose of effecting 15 a deposit of the savings.

My primary object is to provide improved means for locking the casing to the interior body which is provided with several coin-compartments.

20 The present application constitutes a division of my application Serial No. 683,178, filed March 11, 1912.

The invention is illustrated in its preferred embodiment in the accompanying 25 drawings, in which—

Figure 1 represents a longitudinal vertical section of a savings-bank constructed in accordance with my invention; Fig. 2, a view showing the casing in section and the core, or coin receptacle body, in plan, the latter being shown partly in section; Fig. 3, a broken top view of a combination slot-guard and locking-device; Fig. 4, a horizontal section taken as indicated at line 4 30 of Fig. 1, and Fig. 5, a broken transverse section taken as indicated at line 5 of Fig. 1.

In the construction illustrated, A represents a body, or core, provided with money-receptacles, or coin-chambers; and B, a casing 40 which receives the body A and is preferably secured thereto by means of the internal lock which will be presently described.

The body A is of general form now 45 known, comprising a base 1 and coin-receptacles 2 rising from said base.

In the illustration given, the casing is of oval or elliptical cross-section, and the coin-receptacles are grouped about a central bill-chamber 3 into which bills may be inserted 50 through bill-opening 4 in the base 1. One of the chambers 2 opens into or coalesces with the central chamber 3, so that this particular chamber 2 may be used optionally 55 to hold bills or coins. The body has its base

1 of a form corresponding with the contour of the casing B, and the body is adapted to fit snugly within the casing.

The coin-chambers preferably are formed integral with the base and have open upper 60 ends and open or slotted outer sides, as shown. Thus, the coin-chambers are formed by flanges 5 which rise from the base 1. The flanges which form the end receptacles are provided at their upper ends with extensions 5^a, which are provided with slots 5^b, adapted to receive the locking-bolts carried by the upper wall of the casing B.

The casing B preferably comprises a top-plate 6 of oval form and a depending peripheral wall or flange 7, which telescopically receives the body A; thus the peripheral wall 7 provides the outer walls of the coin-chambers 2. The peripheral wall of the casing is provided in its upper portion 75 with coin-slots 8, which register with the upper ends of the several coin-compartments 2, so that coins can be passed, by lateral insertion, into the upper portions of the coin-chambers, to permit which action the flanges 5 are cut away at their upper portions, as indicated at 9. The vertical wall of the casing is also provided with vertical slots 10, associated with graduations (not shown) thus enabling the amount of money in each coin-receptacle to be ascertained at a glance.

Applied to the inner surface of the top of the casing is a lock-carrying and guard-carrying plate 12, which may be of cast metal, and which is preferably secured by means 90 of clenching-lugs 13 (Fig. 5), formed integrally with the top member 6 of the casing, extending downwardly through perforations in the plate 12 and clenched upon lugs 14 with which the lower face of the plate 12 is provided, the lugs 14 having beveled lower surfaces, as shown. Clenching-members 13 are disposed on opposite sides of the lock and centrally of the length of the top member 6 of the casing. The casing-top 6 is further provided, as shown in Fig. 2, with an inwardly struck lug 15, which enters the slot 16, with which the plate 12 is provided, to insure proper positioning of the plate 12.

At the central portion of the plate 12 is a lock-casing 17 formed by a central rectangular depending embossment on the casting 12. The embossment 17 is provided with a chamber 18 which opens at its upper 110

side; and said chamber receives the flat locking-bolts 19 and a superposed filler or plate 20, which is thus located between the locking-bolts 19 and the top wall 6 of the casing. The upper surfaces of the plate or casting 12 and the filler 20 are provided with complementary recesses 21 and 22, respectively, which accommodate a U-shaped spring 23, whose arms are provided with 10 down-turned extremities 24, which pass through slots 25 in the filler and enter perforations 26 in the bolts 19. The lower wall of the chamber 18 is recessed, as indicated at 25^a, to accommodate the lower ends of the downturned extremities 24 of the spring.

The casing top is preferably equipped with a name-plate 27, which may be secured by rivets 28. The name-plate, the top-wall 6, the filler 20, and the lower wall of the chamber 18, are provided with registering perforations adapted to receive a rotatable key-barrel 29. The key-barrel is slotted in the usual way to receive a key. The central opening 30 of the filler is provided 20 with an internal annular rib 31, crossed by a slot 32, where the key may enter. The rib 31 is adapted to register with a slot in the key. Obviously, the location of the rib 31 may be varied; that is, placed in different horizontal planes on different banks 25 to provide for changing the keys. The rib 31 is provided with a lug or lugs 33, as shown in Figs. 2 and 4, to insure the key being turned in the right direction in unlocking the bank. It will be understood 30 that the spring 23 serves to throw the bolts into engagement with the slots 5^b with which the core is provided. To permit the bolts to project from the lock-casing, the end walls 40 of the chamber 18 are provided with slots, as indicated at 34. The bolts are shouldered to limit their outward movement.

It will be understood that the bolts 19 are 45 of such formation that when the key is inserted and rotated, the key will serve to retract the bolts against the force of the spring 23.

The peripheral portion of the plate, or casting, 12, is equipped with outwardly and 50 downwardly projecting lugs 35, which have their lower walls cut away, as indicated at 36, to permit the insertion of coins. The lugs 35 are provided with slots 37 and serve as guides for coin-slot guards 38, which are 55 movable in said slots and normally pressed outwardly into contact with the inner surface of the peripheral wall 7 of the casing by means of springs 39 confined in sockets afforded by the inner ends of the slots 37, 60 as shown in Fig. 1.

The manner of using a safe of this character is now generally understood. The body A is inserted in the casing B, the base

1 of said body serving to close the lower end of said casing. By means of a suitable 65 key, the locking-bolts 19 may be retracted to permit the parts to be brought together, whereupon the bolts, when released, will enter the sockets 5^b and securely lock the 70 parts together. Coins are inserted through the slots 8, the guards 38 yielding to permit the coins to enter. Normally, the guards 75 effectually block the coin-slots, so that the coins, once inserted, cannot be removed through the coin-slots. The coins fall into 80 the receptacles and are maintained therein in stacked relation. When desired, a key 85 may be employed, by authorized parties, to disconnect the casing from the body A, whereupon the casing may be lifted off, 90 leaving the contents accessible. The coins in the receptacles 2 will be found arranged according to denomination, in stacked relation, thus facilitating counting and handling.

The safe described can be manufactured at moderate cost, is durable, secure, and thoroughly practicable from the standpoint of manufacture. The locking-device is exceedingly simple and effective.

The foregoing detailed description has been given for clearness of understanding only, and no unnecessary limitation should be understood therefrom.

What I regard as new, and desire to secure by Letters Patent, is—

1. In a savings-bank, the combination of a body equipped with coin-chambers, a casing, a plate applied to the top-wall of said casing and having a lock-chamber formed 100 therein, a pair of oppositely movable bolts in said lock-chamber, a filler in said lock-chamber above said bolts, said filler having openings therein, and a bent spring having 105 arms provided with down-turned extremities extending through the openings in said filler, and engaging perforations in said bolts.

2. In a savings bank, the combination of a body equipped with coin-chambers, a casing, a plate applied to the top-wall of said casing and formed with a lock-chamber, a pair of oppositely movable bolts in said lock-chamber, a filler in said lock-chamber above said bolts, said filler and plate provided with complementary spring-receiving recesses, and a bent spring received in said recesses and having arms provided with 115 down-turned extremities extending through openings in said filler and engaging said 120 bolts.

CHARLES FISHER.

In presence of—

CHAS. R. KNAPP,
LOLA FISHER.
